US00D586232S

(12) **United States Design Patent**
Friebe et al.

(10) **Patent No.:** **US D586,232 S**
(45) **Date of Patent:** **** Feb. 10, 2009**

(54) **FOIL PACKAGE**

(75) Inventors: **Joachim Friebe**, Heimertingen (DE);
Andreas Michalsky, Memmingen (DE);
Maurice Habram, Kempten (DE);
Agata Surdziel, Kempten (DE); **Peter Ganz**, Untrasried (DE)

(73) Assignee: **Huhtamaki Ronsberg, Zweigniederlassung der Huhtamaki Deutschland GmbH & Co. KG (DE)**

(**) Term: **14 Years**

(21) Appl. No.: **29/299,503**

(22) Filed: **Dec. 27, 2007**

Related U.S. Application Data

(62) Division of application No. 29/231,547, filed on Jun. 7, 2005.

(30) **Foreign Application Priority Data**

Apr. 19, 2005 (EP) 000330485

(51) **LOC (9) Cl.** **09-05**

(52) **U.S. Cl.** **D9/707**

(57) **CLAIM**

The ornamental design for a foil package, as shown and described.

DESCRIPTION

FIG. 1 is a front side perspective view of a foil package showing our new design;

FIG. 2 is a right side perspective view thereof;

FIG. 3 is a bottom view thereof;

FIG. 4 is a front view thereof;

FIG. 5 is a perspective view thereof; and,

FIG. 6 is a top view thereof.

The broken lines shown in the drawings are for illustrative purposes only and form no part of the claimed design.
